UNITED STATES PATENT OFFICE

97,751

DESIGN FOR A HEEL

John Edward Harriss, Lynnfield, Mass.

Application October 9, 1935, Serial No. 58,893

Term of patent 3½ years

To all whom it may concern:

Be it known that I, John Edward Harriss, a citizen of the United States of America, residing in Lynnfield, county of Essex, and State of Massachusetts, have invented a new, original, and ornamental Design for a Heel, of which the following is a specification, reference being had to the accompanying drawing, forming part thereof, wherein,

Figure 1 is a back view of a heel showing my new design.

Figure 2 is a side view of the heel shown in Figure 1.

Figure 3 is a bottom plan view of the same.

I claim:

The ornamental design for a heel, substantially as shown.

JOHN EDWARD HARRISS.
